UNITED STATES PATENT OFFICE.

MAURICE P. SCHWARTZ, OF INDIANAPOLIS, INDIANA.

CABINET.

1,378,285.

Specification of Letters Patent.

Patented May 17, 1921.

Application filed October 22, 1920. Serial No. 418,795.

To all whom it may concern:

Be it known that I, MAURICE P. SCHWARTZ, a citizen of the United States, residing at Indianapolis, in the county of Marion and 5 State of Indiana, have invented a new and useful Cabinet, of which the following is a specification.

It is the object of my invention to lock all the withdrawable drawers of a cabinet having 10 a plurality of tiers of withdrawable drawers by the pushing in of one of such drawers and locking it.

My invention has particular reference to the locking of the drawers or withdrawable 15 boxes of a druggist's cabinet of the general type shown in my prior Patent No. 946,467, granted January 11, 1910.

The accompanying drawing illustrates 20 my invention: In such drawing, Figure 1 is a perspective rear view of a druggist's cabinet embodying my improved lock, with some 25 of the drawers partially pulled out; Fig. 2 is a fragmentary horizontal section through a portion of such cabinet, including the 30 drawer which effects the locking of the remaining drawers; Fig. 3 is a perspective view of a fragment of one of the slidable locking bars; Fig. 4 is a plan of a fragment of one of the locking bars mounted in place 35 in its floor board and showing the associated pivot pin of a withdrawable drawer; Fig. 40 5 is a fragmentary section on the line 5—5 of Fig. 2; and Fig. 6 is a front elevation of the cabinet on a smaller scale.

The cabinet consists of a usual casing having side walls 10 and a plurality of transverse horizontal shelves 11, which include 40 those at the top and bottom and provide space for a plurality of tiers of withdraw- 45 able drawers 12, the cabinet shown having four tiers of five drawers each, and each tier of drawers having a shelf above it as well as below it so that there are five such shelves. The drawers 12 are provided near 50 one rear corner with upwardly and downwardly projecting pins 13, which extend into slots 14 in the lower and upper surfaces of the adjacent shelves 11. The shelves project forward beyond the drawers 55 when the latter are shoved back, and the slots 14 extend forward beyond the front ends of the shoved-back drawers; so that when the drawers are pulled forward the pins 13 are guided by the slots 14, which 60 limit the forward movement of the drawers and permit a drawer to be swung about its pins 13 as a pivot when such pins have been drawn to the front end of the associated slots 14, to give access to the drawer from the side and permit it to be closed on the other side 65 as well as on the front and back and bottom and top.

Near its rear edge, the upper surface of each shelf 12 is provided with a transverse slot in which is mounted a slidable bar 15, which at one end is connected by a link 16 to an arm 17 fixed on a vertical rod 18 suitably mounted for turning in a recess on the inner face of one of the side walls 10. The rod 18 is turned in opposite directions by 70 pulling out and pushing in one of the drawers which lies against such side wall, say the right hand drawer 12' of the second tier from the top as viewed from the front. For this operation, the rod 18 has two 75 arms 19 and 20 which coöperate with the rear wall 21 of the drawer 12', so that when such drawer is pulled forward the rear wall 21 strikes the arm 19 and turns the rod 18 in one direction and when such drawer is 80 pushed back the rear wall strikes the arm 20 and turns the rod 18 in the other direction. These opposite turning movements of the rod 18 slide the bars 15 in opposite directions, all such bars operating correspondingly. The bars 15 are thicker (vertically) 85 than the depth of the slots 14, and are provided with notches 22 the bottoms of which are in the same horizontal planes as the bottoms of the slots 14. By the sliding of the 90 bars 15 the notches 22 are brought either into line with the slots 14, to unlock the drawers, as shown in Fig. 1, or are moved out of the line of such slots, to lock the drawers by closing the slots 14 in front of the 95 pivot pins 13 of the shoved-back drawers, as shown in full lines in Fig. 4. Each notch 22 except that for the drawer 12' has one side wall 23 horizontally inclined in both 100 directions from a point near the front edge of the bar 15, so that when such bar is shoved to the right (Figs. 1 and 4) to close the associated slots 14 such inclined walls 23 will engage the pivot pins 13 of any drawers which are not shoved fully back and by 105 their cam action on such pins will either shove the drawers completely back and lock them in place or will shove them farther forward to call attention to the fact that they are not locked, as will be clear from 110

the dotted and full-line positions in Fig. 4. In order that this cam action may produce movement of the pins 13 along the slots 14, and not along the line of movement of the 5 bars 15, staples 24 are driven into the shelves 11 over the bars 15 at the right-hand side (Figs. 1 and 4) of each slot 15; these staples prevent the pins 13 from being carried transversely of the slots 14 by the action of 10 the sliding bars 15.

A notch 22 is provided in the bars 15 for each downwardly extending pin 13 of each 15 drawer; and as stated, all these notches 22 are similar and are provided with the inclined wall 23 with the exception of the notch 22' for the pin on the drawer 12'. This notch 22' is made of sufficient width, lengthwise of the bar 15, so that its walls never cross the associated slot 14 and so that 20 that particular slot 14 is never closed. This permits the drawer 12' to cause turning of the rod 18 to lock and unlock the remaining drawers as the drawer 12' is shoved in or pulled out, and avoids interference with 25 such shoving in and pulling out an account of any interlocking of the bar 15 with the pivot pin 13 of that drawer. The drawer 12' is provided with a suitable lock 25, usually a key lock, by which such drawer may 30 be locked in closed position; and this locks all the drawers of the cabinet.

I claim as my invention:

1. In a cabinet, the combination of a casing, a horizontal series of drawers mounted 35 in said casing and having pins projecting vertically therefrom, a slideable bar mounted in said casing to slide transversely of the drawer movement, said bar being arranged to interlock with said pins to prevent or 40 permit the withdrawal of drawers, and means operated by one of said drawers for moving said bar.

2. In a cabinet, the combination of a casing having a plurality of shelves, a plurality 45 of drawers mounted on each shelf, said drawers being provided with pins which project vertically therefrom, a bar associated with the drawers on each shelf and slideable transversely of the drawer movement, said bars and pins on the associated 50 drawers being arranged to interlock to prevent or permit withdrawal of such associated drawers, a common operating device for operating all said bars, and means for 55 actuating said operating device by the withdrawal or shoving in of one of said drawers.

3. In a cabinet, the combination of a casing having a plurality of shelves, a plurality 60 of drawers mounted on each shelf, said drawers being provided with pins which project vertically therefrom, a bar associated with the drawers on each shelf and slideable transversely of the drawer movement, said bars and pins on the associated 65 drawers being arranged to interlock to pre-

vent or permit withdrawal of such associated drawers, and a common operating device for operating all said bars.

4. In a cabinet, the combination of a horizontal series of drawers each having pivot 70 pins projecting upwardly and downwardly therefrom, a casing having horizontal members respectively above and below said horizontal series of drawers, said horizontal members being provided with grooves in 75 which said pins slide as the respective drawers are drawn forward or shoved rearward, and a transverse bar slidably mounted in one of said horizontal members to slide transversely in said slots, said horizontally 80 slidable bar being provided with notches which are moved into and out of registry with said slots by the sliding of said bar to permit or prevent withdrawal of said 85 bars.

5. In a cabinet, the combination of a horizontal series of drawers each having pivot pins projecting upwardly and downwardly therefrom, a casing having horizontal members respectively above and below said horizontal series of drawers, said horizontal members being provided with grooves in 90 which said pins slide as the respective drawers are drawn forward or shoved rearward, and a transverse bar slidably mounted in one of said horizontal members to slide transversely of said slots, said horizontally 95 slidable bar being provided with notches which are moved into and out of registry with said slots by the sliding of said bar to permit or prevent withdrawal of said 100 bars, said notches having horizontally inclined walls on one side so that when the bar is moved to locking position said inclined walls will act on the 105 pins of any drawer not shoved completely back to move said drawer along its slots.

6. In a cabinet, the combination of a horizontal series of drawers each having pivot pins projecting upwardly and downwardly therefrom, a casing having horizontal members respectively above and below said horizontal series of drawers, said horizontal members being provided with grooves in 110 which said pins slide as the respective drawers are drawn forward or shoved rearward, a transverse bar slidably mounted in one of said horizontal members to slide transversely of said slots, said horizontally 115 slidable bar being provided with notches which are moved into and out of registry with said slots by the sliding of said bar to permit or prevent withdrawal of said 120 bars, and means actuated by the pushing in or pulling out of one of said drawers for 125 sliding said bar to locking or unlocking position.

7. In a cabinet, the combination of a casing having two horizontal members, a horizontal series of drawers mounted between 130

said two members, a transversely slidable bar mounted in one of said members, and means actuated by pulling out or pushing in one of said drawers for sliding said bar, 5 each of the other drawers being provided with a vertically projecting pin arranged to coöperate with said bar, and said bar being provided with notches which may be moved into and out of registry with the paths 10 which such pins have in the movement of the associated drawers.

8. In a cabinet, the combination of a sliding drawer, a casing having two members, said two members being provided with

guide slots in the direction of the sliding 15 of said drawer, pins mounted on said drawer and projecting into said slots and serving as pivot pins upon which the drawer can be turned when the pins are drawn to one end of the slots, and locking means releasably coöoperating with one of said pins to lock the drawer when the pin is in the other end of said slot.

In witness whereof I have hereunto set my hand at Indianapolis, Indiana, this 16th 25 day of October, A. D. one thousand nine hundred and twenty.

MAURICE P. SCHWARTZ.
